COMBINATION STORING AND STACKING CASE

Günther Schanz, Frankfurt am Main, Germany, assignor to Johann Saar G.m.b.H., Gravenwiesbach, Germany

Filed June 17, 1959, Ser. No. 56,383

Term of patent 14 years

(Cl. D58—12)

FIG. 1 is a perspective view of a combination storing and stacking case, showing my new design.

The side and the rear not shown are the same as the side shown.

What I claim is:

The ornamental design for a combination storing and stacking case, as shown and described.
